PNEUMATIC FIBER PLACING MACHINE

William F. Bokum, Jenkintown, Pa., and Charles F. Hine, San Francisco, Calif., assignors to The Pacific Lumber Company, San Francisco, Calif., a corporation of Maine

Application July 8, 1941, Serial No. 401,478

8 Claims. (Cl. 302—37)

This invention relates to apparatus for pneumatically forcing fibrous insulating materials through a pipe for placing the materials in wall spaces for the thermal insulation of the walls, and for other uses.

The objects of the invention are to provide improved apparatus which will more expeditiously handle chunks of baled shredded bark fiber, and effectively deliver the fiber in uniformly loosened up condition. Specific advantages and features of the invention will appear in the following description and accompanying drawings.

In the drawings—

Fig. 1 is a perspective view of our improved pneumatic fiber placing machine showing its feed hopper and outlet or placing pipe, and driving engine.

Fig. 2 is an enlarged cross section of the centrifugal ejector, taken from the line 2—2 of Fig. 1.

Fig. 3 is an enlarged longitudinal central vertical cross section of Fig. 1 with the driving engine omitted.

Fig. 4 is a cross section of the picking cylinder taken from the line 4—4 of Fig. 3.

Before describing the drawings in detail it may be said that the machine as shown in Fig. 1 comprises a base or bed plate 1 upon which is mounted an internal combustion engine 2 (or other prime mover) the shaft of which directly operates devices for thoroughly opening up and loosening compact masses of shredded bark fed into the hopper 3 and ejecting the fluffed up mass in an air stream forced out of pipe 4 by means of a centrifugal blower 5.

It is of course recognized that power blowers have been used for ejecting all sorts of materials through piping, including shredded bark fiber, and such apparatus has been heretofore used by applicants' assignees, but the condition of the finally placed fiber was not entirely satisfactory as it was not uniformly or evenly separated or fluffed up, but on the contrary carried in it considerable fiber which was lumpy and unsuitable for best thermal results, whereas with the improved apparatus of the present invention the defects mentioned are entirely overcome.

In further detail the projecting engine crank shaft is designated 6 and it extends through an opening 7 in one side wall 8 of the blower casing 5 and directly supports the hub 9 of the blower wheel 10 within the casing. The shaft 6 does not extend entirely through hub 9 but terminates at dotted line 11 at a point spaced inwardly from the remote end of the hub and is secured to the hub as by a key 12 and set screw 13, while pro-

jecting into the free portion of the bore of the hub thus provided is a continuing shaft 14 which extends horizontally through an elongated cylindrical shell or casing 15 and is rotatably supported at its outer end by a bearing 16 secured to a plate 17 closing the end of the cylinder.

Shaft 14 is provided at its inner end with a transversely extending driving pin 18 projecting at both ends into slots 19 cut in the end of hub 9—the arrangement being to permit easy connection and separation of shaft 14 from hub 9, as well as to obviate the otherwise necessity of accurately aligning the shafts. The adjacent side wall 8' of the blower casing is also made separable on the outer side of the blower as by bolts 20. Spaced along shaft 14 and secured thereto as by welding is a series of tapering two rounded edge picker blades 21 alternately arranged at right angles as indicated, and projecting inwardly from the cylindrical casing 15 is a plurality of pointed pins 22 or sharpened screws. These pins are arranged in several rows along the upper and both sides of the casing only as the lower half of the casing is left clear for the easy passage of material to the blower housing, and through the center of one side of which blower housing the end of the cylindrical casing 15 opens and connects thereto by a flange joint 23 removably secured in place as by screws 24. Pointed pins 22 are threaded so that their projection into the casing 15 may be adjusted. The taper of the picker blades avoids snarling up of the fiber on the picker shaft.

Adjacent the outer end of casing 15 is a vertically extending chute 25 formed with a flaring hopper 3 on its upper end, while at the extreme outer end of cylindrical casing 15 is one or more air inlet openings 26 which may be more or less closed off by an adjustable shutter 27. It should be noticed that these air inlets are adjacent the unobstructed bottom wall of casing 15.

It should be noted that the cylindrical picker shell 15 is only about a third the diameter of the blower wheel 10, and that the picker blades 21 are about a quarter the diameter of the blower wheel, as this keeps down the peripheral speed so the picker will pick apart the lumps of fiber and not destructively disintegrate and destroy it.

The form of the blower wheel 10 has been developed after considerable experiment to meet the special requirements of handling shredded redwood bark fiber, and consists of a solid rear disk 10 secured to the hub 9 as by welding

and to the forward face of which disk a plurality of spaced radial vanes 28 are secured along their rearmost edges only as by welding, and the inner ends of the vanes are similarly secured to the hub 9.

Disk 10 is conically dished forwardly over the greater part of its diameter to about half the breadth of the vanes 28 where it meets the hub 9 as indicated at 10', and is rigidly braced in this dished position as by a plurality of angular plates 29 welded to the disk as well as to hub 9. Vanes 28 are broadest at their outer ends and tapered toward the hub to fit the dished form of the disk 10 and are also similarly tapered on their forward edges to about half this amount, thus providing a space between the forward edges of the vanes and the wall 8' of the blower housing which becomes narrower toward the ends of the vanes. The outer ends 28' of the vanes are curved backward or in a direction opposite the direction of rotation of the impeller wheel indicated by the arrow.

The outer end of the casing 15 is secured to and supported in horizontal extension on a bracket 30 and the engine 2 is similarly supported on a pedestal 31, all in turn secured to the base plate or frame 1, so as to make a rigid portable assemblage, the moving about of which is facilitated by provision of a rail handle 32.

The use of a gasoline engine as the prime mover is preferable to an electric motor for the reason that in order to drive a blower wheel of about two feet in diameter at the speed desired, about five horsepower is required, and normally the power sockets available in home districts where these machines are frequently used in filling the studding spaces of the houses with shredded bark fiber, are not wired heavy enough for the current required. The engine also permits the machine to be used on new work before the electric installations have been made, and is also less expensive to run. Besides by reason of the greater power through use of an internal combustion engine it has been possible to reduce the size of the placing pipe from the 5" diameter formerly used, to 3" diameter.

While the machine may be used to fluff up and pneumatically place any kind of fibrous material, it has been especially designed to handle finely shredded redwood bark fiber as furnished for thermal insulation purposes. This bark fiber is supplied in tightly packed bales, and when the bales are opened it may be separated in layers several inches thick and chunks and slab-like pieces broken off by hand. These chunks and pieces are dropped or fed into the hopper 3 while the machine is running, and are at once torn apart by the high speed pickers of shaft 14 cooperating with the pointed pins 22 and completely separated and fluffed up before entering the impeller wheel housing with the suction air stream.

The fluffed up material passes generally along the bottom wall of cylinder 15 together with air drawn in from louver openings 26, though additional air enters with the chunks of material constantly being fed into chute 25, and by the form of the impeller wheel being tapered away from its housing wall 8' where the fluffed up material enters it is less destructive to the material, but brings it up to speed and ejects it through the outlet pipe 4 with less breakage.

of fiber and production of objectionable dust than prior machines used for this purpose.

Having thus described our improved pneumatic bark fiber placing machine, what we claim is:

1. A pneumatic placing machine for handling baled insulating fiber comprising a rotary blower having a housing with a multivane impeller wheel therein, a power shaft extending through one side of the housing supporting the impeller, a cylindrical casing secured at one end to and extending laterally from the opposite side of said housing and open at said end to the impeller space, a picker shaft extending through said cylindrical casing connected at its inner end to said power shaft and supported at its outer end by a bearing carried by said casing, cooperating picker elements projecting from said picker shaft and said casing, means closing the outer end of said casing, a feed chute extending upwardly from said casing, means for admitting air to the outer end of said casing, and means for adjusting the projection of the picker elements from said casing, the bottom of said casing being free from picker elements.

2. A pneumatic placing machine for handling baled insulating fiber comprising a rotary blower having a housing with a multivane impeller wheel therein, a power shaft extending through one side of the housing supporting the impeller, a cylindrical casing secured at one end to and extending laterally from the opposite side of said housing and open at said end to the impeller space, a picker shaft extending through said cylindrical casing connected at its inner end to said power shaft and supported at its outer end by a bearing carried by said casing, cooperating picker elements projecting from said picker shaft and said casing, and a feed opening in the wall of said casing, the vanes of said propeller wheel being generally radially disposed and of greatest breadth adjacent their outer ends and tapered narrower toward said power shaft along their edges adjacent said casing and curved away from the direction of rotation at their outer ends.

3. A pneumatic placing machine for handling baled insulating fiber comprising a rotary blower having a housing with a multivane impeller wheel therein, a power shaft extending through one side of the housing supporting the impeller, a cylindrical casing secured at one end to and extending laterally from the opposite side of said housing and open at said end to the impeller space, a picker shaft extending through said cylindrical casing connected at its inner end to said power shaft and supported at its outer end by a bearing carried by said casing, cooperating picker elements projecting from said picker shaft and said casing, and a feed opening in the wall of said casing, the vanes of said propeller wheel being generally radially disposed and of greatest breadth adjacent their outer ends and tapered narrower toward said power shaft along their opposite edges, and a conically dished disk secured to the edges of said vanes remote from said casing.

4. A pneumatic placing machine for handling baled insulating fiber comprising a rotary blower having a housing with a multivane impeller wheel therein, a power shaft extending through one side of the housing supporting the impeller, a cylindrical casing secured at one end to and extending laterally from the opposite side of said housing and open at said end to

the impeller space, a picker shaft extending through said cylindrical casing connected at its inner end to said power shaft and supported at its outer end by a bearing carried by said casing, cooperating picker elements projecting from said picker shaft and said casing, and a feed opening in the wall of said casing, said casing being removably secured at its end to said housing, said impeller provided with a hub secured to said power shaft, the inner end of said picker shaft provided with a transversely projecting pin, and the outer end of said hub being transversely slotted to receive said pin with the end of the shaft in the bore of the hub together with said power shaft.

5. A pneumatic placing machine for handling baled insulating fiber comprising a rotary blower having a housing with a multivane impeller wheel therein, a power shaft extending through one side of the housing supporting the impeller, a cylindrical casing secured at one end to and extending laterally from the opposite side of said housing and open at said end to the impeller space, a picker shaft extending through said cylindrical casing connected at its inner end to said power shaft and supported at its outer end by a bearing carried by said casing, cooperating picker elements projecting from said picker shaft and said casing, and a feed opening in the wall of said casing, said impeller provided with a hub bored for said power shaft, said vanes being of sheet metal extending substantially parallel to the axis of the power shaft of greatest breadth adjacent their outer ends and tapered narrower toward the hub along forward and rear edges, a conically dished disk in contact with the rear edges of the vanes and welded thereto and to said hub, and radially extending bracing plates welded to the hub and to the dished rear side of said disk, said vanes being generally straight and radially disposed but with outer ends curved away from the direction of rotation.

10 7. A portable pneumatic fluffing and placing machine for insulating fiber comprising a base, a blower housing carried on said base, an internal combustion engine on said base with the impeller of said blower carried on the engine shaft, an elongated cylindrical picker casing not over half the diameter of the blower impeller extending laterally from the intake side of said blower housing and provided with an upwardly extending feed chute, a bracket supporting the outer end of said casing to the base, a picker 15 shaft in said casing removably coupled at one end directly to said impeller, cooperating picker elements carried by said casing and picker shaft formed to loosen up compacted fibers, and a bearing supporting the outer end of said picker shaft.

20 8. A pneumatic placing machine for handling baled insulating fiber comprising a rotary blower having a housing with a multivane impeller wheel therein, a power shaft extending horizontally through one side of the housing supporting the impeller, an elongated cylindrical casing of much less diameter than the blower housing secured at one end to and extending laterally from the opposite side of said housing and open at said end to the impeller space, a picker shaft in said cylindrical casing removably connected at one end to said power shaft, cooperating picker elements projecting from said picker shaft and said casing, and a feed 25 opening in the wall of said casing, the picker elements projecting from the shaft arranged therealong in staggered relation to the elements on the casing and being of a diameter not over one third the diameter of said impeller and formed to pick apart and loosen up the compacted fibers fed into said casing so as to all pass freely by suction into said blower.

30 40 45 50 55

6. A pneumatic placing machine for handling baled insulating fiber comprising a rotary blower having a housing with a multivane impeller wheel therein, a power shaft extending through one side of the housing supporting the impeller, a cylindrical casing secured at one end to and extending laterally from the opposite side of said housing and open at said end to the impeller space, a picker shaft extending through said cylindrical casing connected at its inner end to said power shaft and supported at its outer end by a bearing carried by said casing, cooperating picker elements projecting from said picker shaft and said casing, and a feed opening in the wall of said casing, said impeller
